WAVE GUIDE WITH MODE SUPPRESSION MEANS

William Spencer Percival, Ealing, London, England, assignor to Electric & Musical Industries Limited, Hayes, Middlesex, England, a company of Great Britain

Application August 2, 1946, Serial No. 688,165
In Great Britain May 12, 1943

Section 1, Public Law 690, August 8, 1946
Patent expires May 12, 1963

2 Claims. (Cl. 178—44)

1

This invention relates to electric waveguides and has for its object to provide means whereby waves of the so-called E mode, such as E_0 waves, can be propagated along a guide and undesired waves of the so-called H mode, such as H_1 waves, can be eliminated from the guide or substantially attenuated. The present invention provides a simple and effective means whereby such elimination can be accomplished.

The present invention is based on the fact that a narrow longitudinal slot in a guide will allow waves of H mode to escape while having a negligible effect upon waves of E mode, so that waves of the latter mode will be transmitted along the guide while waves of H mode will be attenuated.

According to the invention there is provided an electric waveguide for the transmission of waves of the E mode coupled to a source of said waves and having undesired waves of the H mode present in said guide, wherein said guide is provided with one or a plurality of slots arranged longitudinally of said guide, the size of said slot or slots being such as to afford substantial attenuation of said undesired waves. A plurality of said slots may be provided spaced equidistantly around the circumference of said guide and, if desired, a plurality of sets of said slots are provided each set being spaced longitudinally of said guide. Where the said slot or slots is or are provided in a guide formed of a conducting tube, a conducting sleeve or sleeves may be provided axially movable with respect to said tube for the purpose of adjusting the length of said slot or slots.

In order that the said invention may be clearly understood and readily carried into effect, it will now be more fully described with reference to the accompanying drawings, in which:

Figure 1 illustrates a portion of a waveguide provided with means in accordance with the preferred form of the invention, and

Figure 2 illustrates a portion of a waveguide provided with means in accordance with another embodiment of the invention.

In the embodiments of the invention shown in Figures 1 and 2, the section of the waveguide illustrated is intended to transmit waves of E_0 mode and to eliminate or substantially attenuate waves of H_1 mode.

Referring first to Figure 1 of the drawings, the waveguide illustrated comprises a conducting tube 3 of circular form in cross-section having an internal diameter of one and one-eighth inches and a wall thickness of one-sixteenth of

an inch and is intended to transmit waves of E_0 mode which in air have a wavelength of 3.2 cms. The guide is provided with four filter sections each comprising a plurality of sets of longitudinal slots 4, 5, 6 and 7, eight slots being provided in each section equidistantly spaced around the circumference of the guide. The optimum length of each slot is found to be about 1.5 times the wavelength of the waves to be propagated in the guide and where waves of a wavelength of 3.2 cms. are required to be transmitted, the optimum length of each slot is 4.5 cms. The width of each slot is one-sixteenth of an inch and the spacing between the slots in the adjacent sections is 3 cms., although this spacing is not critical.

H waves when travelling along a guide set up circumferential currents in the guide due to their axial magnetic field and the effect of the slots above described is to present a high impedance to the circumferential currents which thus set up a potential difference across the slots and hence causes radiation of H_1 waves. The filter acts like an impedance in the guide which has no measurable effect on E_0 waves but reflects or absorbs nearly all the power of the H_1 waves. Since a considerable fraction of the power of the H_1 waves is absorbed this is advantageous compared with a filter which operates entirely by reflection since, in general, it is not possible to build up high H_1 voltages in the guide on the source side of the filter. If desired, it is possible by suitably choosing the length of the slots forming the filter section nearest the source to adjust the impedance of the filter to match the impedance of the source of H_1 waves. The length of the slots may be adjusted by the provision of an axially movable conducting sleeve 8.

In the embodiment of the invention shown in Figure 2 the guide 3 is provided with two filter sections each comprising a plurality of slots 9 and 10 spaced apart as indicated. Each section has four slots arranged longitudinally with respect to the axis of the guide and equidistantly spaced around its circumference. The slots 9 and 10 are substantially longer than the slots shown in Figure 1 and are partially covered by conducting sleeves 11 and 12 which are arranged for axial movement along the length of the slots 9 and 10. In one specific example for waves with an air wavelength of approximately 3.2 cms., the length of the slots 9 and 10 are five and one-eighth inches, the two sections being spaced apart by one and one-quarter inches, although this latter distance is not believed to be critical. The length of each sleeve 11 and 12 is one inch and with

the sleeves 11 and 12 arranged 1.79 inches from the left and right hand ends of the sections respectively, maximum attenuation of the H_1 waves occurred although not to the same extent as the attenuation obtained with the arrangement of Figure 1.

The present invention is of particular use in apparatus for measuring impedances. It will be appreciated that in such apparatus it is necessary to isolate the impedance measuring apparatus from possible sources of H_1 waves in the source of E_0 waves and in the impedance to be measured. By inserting a filter as described above between the measuring apparatus and the source and between the measuring apparatus and the impedance to be measured, this isolation can be readily accomplished.

Although in the above description the filters described each employ a plurality of sections, it will be understood that any desired number of sections can be employed. The number of slots is also not limited to either 4 or 8.

What is claimed is:

1. An electric wave guide for the transmission of waves of the E mode to the exclusion of waves of the H mode, comprising a hollow conducting member having a plurality of slots arranged longitudinally therein and communicating with surrounding space, and a conducting sleeve axially moveable with respect to said member to ad-

just the apertures of said slots to lengths at which undesired waves of the H mode present in said guide are substantially attenuated.

2. An electric wave guide for the transmission of waves of the E mode to the exclusion of waves of the H mode, comprising a hollow conducting tube having a plurality of sets of slots open to free space arranged longitudinally of said tube, the slots of each set of slots being spaced equidistantly about the circumference of said tube, and conducting sleeves surrounding said tube, said sleeves being axially moveable with respect to said tube to present openings of said slots having lengths at which undesired waves of the H mode present in said guide are substantially completely attenuated.

WILLIAM SPENCER PERCIVAL.
